RAIL LUBRICATOR

Thomas Albert Sprake Munford, Toronto,
Ontario, Canada

Application July 25, 1935, Serial No. 33,110

7 Claims. (Cl. 184—3)

My invention relates to improvements in rail lubricators and the object of the invention is to devise an apparatus which will deposit a line of grease in the form of beads on the side of the tread portion of a rail of railroad tracks which will be distributed by the wheel flanges of rolling stock passing thereover, thus lubricating the wheel flanges and the rail tread side and preventing wear thereon which occurs on curves of 10 the right-of-way.

A further object is to devise a simple, compact and comparatively light apparatus which can be operated by one man, and which will be comparatively cheap to manufacture.

15 A still further object is to construct a device which will deposit the grease on the rail under continuous pressure, and yet another object is to provide adjustable means for enabling the device to be operated on rails in which the width 20 of the rail tread varies.

With the above and other objects in view which will hereinafter appear as the specification proceeds, my invention consists, in its preferred embodiment, of the construction all as herein- 25 after more particularly described and illustrated in the accompanying drawing in which:—

Fig. 1 represents my apparatus partly in section and partly in side elevation showing the same applied to the rail of a track.

30 Fig. 2 is a front elevational view of the lower portion of my device.

Fig. 3 is an enlarged vertical cross sectional view, and

Fig. 4 is a plan view of the portion of my de- 35 vice or shoe applied to the rail of the track.

Like characters of reference indicate corresponding parts in the different views.

The portion of my device adapted to be applied to the rail, which may be termed a shoe, 40 consists of a substantially rectangular frame 1 in which transverse flanged rollers 2 are journaled in the vicinity of its ends.

Intermediately of the rollers 2, I provide a U-shaped member 3, the legs 4 of which extend 45 freely through the longitudinal portions of the frame 1, and the threaded extremities of the legs 4 carrying nuts 5 adapted to be held against the adjacent longitudinal portion of the frame by means of spiral springs 6 freely mounted on the legs 4 and having their ends respectively abutting the opposite longitudinal portion of the frame, and the nuts 5, which are located on the leg extremities interiorly of the frame.

A depending stud 7 is provided on the base of 50 the U-shaped member 3 exteriorly of the frame

1 upon which is rotatably mounted a roller 8 adapted to engage the side of the tread portion of the rail of the track.

A member 9 having its lower end transversely fulcrumed to the frame 1 between the legs 4 of the U-shaped member 3 has its upper end secured to a grease cylinder 10. The upper end of the latter is closed by a cap 11 having a central bushing 12 protruding therefrom which in turn is connected by a coupling 13 with a tubular handle member 14.

A sleeve 15, having an actuating knob 16 disposed exteriorly of the upper end of the tubular handle member 14, extends freely down there-through into the bushing 12 and is provided with a flanged plug 17 at its lower end. A spiral spring 18 is disposed on the sleeve 15 between the flanged plug 17 and the lower end of the handle member 14, and a plunger rod 19 secured at its lower end to a plunger 20 disposed in the grease cylinder 10 is threaded through the plug 17 extending up into the sleeve 15.

An interiorly threaded cap 21 is adapted to be screwed onto the exteriorly threaded upper end of the handle member 14 for centering the upper end of the sleeve 15.

A grease discharge outlet 22 in the lower end of the grease cylinder 10 is connected by a tube 23, preferably flexible, to a grease passageway 24 in a boss 25 secured to the side portion of the frame 1 opposite to that adjacent to the roller 8, such passageway 24 extending down in the boss 25 and having a grease outlet 26 disposed in the face 27 of the boss abutting the side of the tread portion of the rail. The inclination of the face 27 preferably corresponds substantially with that of the tread portion side of the rail.

As illustrated in Fig. 1, the device can be actuated longitudinally on the rail in either direction.

The frame 1 is applied to the rail as illustrated in Figs. 1 to 3, the face 26 of the boss 25 abutting one side of the tread and the roller 8 engaging the other side, the rollers 2 being adapted to run on the tread of the rail. The provision of the U-shaped member 3 and the spring 6 permits the device accommodating itself to variations in the width of the tread of the rail occasioned by wear, and the nuts 5 permit adjustment of the member 3 in the frame.

In order to feed the grease onto the side of the rail tread in the form of a series of beads (depicted in Fig. 1 as A), the sleeve 15 is rotated by the knob 16 in the required direction with the result that the sleeve will move upwardly.

and through the medium of the attached flanged plug 17 will compress the spring 18. The spring will now exert a downward pressure on the flanged plug 17 forcing down the rod 19 threaded thereto and causing the plunger 20 to move down in the cylinder 10 expelling the grease through the outlet 22, tube 23, passageway 24 and outlet 26, delivering the grease onto the side of the rail tread in the form of a series of beads as the device is pushed along the rail.

When the spring 18 by elongating as above described ceases to exert the required pressure it is only necessary to rotate the sleeve 15 a further extent wherein the spring is again compressed and pressure exerted on the plug 17 and attached plunger rod. Thus, as the apparatus is moved along the rail, the sleeve 15 is intermittently rotated to keep the spring 18 in compression and thus secure a continuous flow of the grease onto the rail.

A lubricator such as described above is particularly applicable for use on the high rail of tracks on curves.

What I claim as my invention is:

1. In a rail lubricator, in combination, a shoe adapted to be moved longitudinally on the tread portion of the rail and comprising a frame including spaced side members, transverse rollers journaled between the side members of the frame and adapted to roll on the tread portion of the rail, a U-shaped member having its legs extending transversely and freely through the side members of the frame with the base of the U disposed exteriorly thereof, nuts threaded on the legs of the U-shaped member and engageable with the interior face of one of the frame side members, spiral springs on the legs of the U-shaped member having their ends engageable respectively with the nuts and with the opposite frame side members, an element depending from the base of the U of the U-shaped member and engageable with one of the sides of the tread portion of the rail, an abutment on the frame engageable with the other side of the tread portion of the rail and including lubricant dispensing means for dispensing lubricant onto a side of the tread portion of the rail, and means for feeding lubricant to such lubricant dispensing means.

2. A rail lubricator as claimed in claim 1 where-
50 in the lubricant dispensing element is incorpo-
rated in the abutment.

3. In a rail lubricator, in combination, a shoe adapted to be moved longitudinally on the tread portion of the rail and comprising a frame including spaced side members, transverse rollers journaled between the side members of the frame and adapted to roll on the tread portion of the rail, a U-shaped member having its legs extending transversely and freely through the side members of the frame with the base of the U disposed exteriorly thereof, nuts threaded on the legs of the U-shaped member and engageable with the

interior face of one of the frame side members, spiral springs on the legs of the U-shaped member having their ends engageable respectively with the nuts and with the opposite frame side members, a depending roller rotatably mounted in the base of the U of the U-shaped member and engageable with one of the sides of the tread portion of the rail, an abutment on the frame engageable with the other side of the tread portion of the rail and having a lubricant passageway therethrough with its discharge end in the face of the abutment engaging the side of the tread portion of the rail, and means for feeding lubricant to the lubricant passageway in the abutment.

4. In a rail lubricator as claimed in claim 1, a member having its lower end transversely journaled between the side members of the frame, a lubricant cylinder mounted on the upper end of said member, means for connecting the lubricant cylinder with the lubricant dispensing element on the frame, and means for feeding the lubricant in the lubricant cylinder to the lubricant dispensing element.

5. In a rail lubricator, in combination, a shoe adapted to be moved longitudinally on the tread portion of a rail in either direction, a lubricant dispensing element on the shoe engageable with a side of the tread portion of the rail, a member transversely journaled at its lower end in the shoe, a lubricant cylinder mounted on the upper end of such member, means for connecting the lubricant cylinder with the lubricant dispensing element on the shoe, and means for feeding the lubricant in the lubricant cylinder to the lubricant dispensing element.

6. In a rail lubricator, in combination, a shoe adapted to be moved longitudinally on the tread portion of the rail and comprising a frame, spaced apart transverse rollers journaled in the frame, a depending abutment on the frame adapted to engage a side surface of the tread portion of the rail, a laterally adjustable depending element on the opposite side of the frame adapted to engage the opposite side surface of the tread portion of the rail to that which the abutment engages, and spring means on the frame co-operating with the depending element for causing the abutment to continually contact the side surface of the rail tread portion at all times irrespective of variations in the width of such tread portion.

7. A rail lubricator as claimed in claim 6 where-
55 in a U-shaped member has its legs extending freely transversely through the frame with the base of the U-shaped member disposed exteriorly thereof and the depending element mounted on the base of the U-shaped member, and the spring means operatively mounted between the frame and the U-shaped member for causing the depending element to resiliently engage the side surface of the tread portion of the rail.

THOMAS ALBERT SPRAKE MUNFORD.
